Primary Examiner — Melanie H Tung(74) *Attorney, Agent, or Firm* — Nwamu, P.C.**CLAIM**

The ornamental design for a computer display with a graphical user interface, as shown and described.

DESCRIPTION

The FIGURE is a front view of our new design for a computer display with a graphical user interface.

The dashed broken lines are for the purpose of illustrating portions of a computer display and window for displaying the computer display with a graphical user interface and form no part of the claimed design.
